Attorney

UNITED STATES PATENT OFFICE.

FRANK H. HOWARD, OF READING, PENNSYLVANIA.

I-BEAM TRAVELER.

Application filed May 13, 1925. Serial No. 29,961.

To all whom it may concern:

Be it known that I, FRANK H. HOWARD, a citizen of the United States, residing at Reading, in the county of Berks and State of Pennsylvania, have invented certain new and useful Improvements in I-Beam Travelers, of which the following is a specification.

This invention relates to improvements 10 in travelers or load carriers, such as are adapted for moving on an I-beam or track, and the object in the present instance is to provide a device of this character in which provision is made for adapting it 15 to a beam of any width within the limits usually employed for devices of this kind.

The invention consists in providing means for adjusting the frame to the width desired, and I accomplish this by providing 20 cross members slidably engaging the longitudinal members of the frame, and a set of tapered keys for securing the relative frame parts in position.

The invention is more fully described in 25 the following specification and clearly illustrated in the accompanying drawing, in which:—

Figure 1 is a side elevational view of my traveler.

Figure 2 is an end elevational view thereof, with the parts adjusted to accommodate a relatively wide beam.

Figure 3 is a like end view, with the parts adjusted to accommodate a relatively narrow beam.

Figure 4 is a sectional view taken through the line 4—4 of Figure 3.

The numeral 1 designates the longitudinal or side frame members, which carry the 40 trolley wheels 2 and which in turn ride on the I-beam 3.

The numeral 4 designates the end or cross members of the frame, and each cross member is formed with an elongated slot 5 which slot is formed with a series of indentations or serrations 6 on its lower surface. The side frame members are slidably adjustable on the end frame members and are secured in position thereon by means of a set of 50 wedges 7, which pass through perforations 8 in the side members and which wedges are formed with serrations on their under surfaces, 9, adapted to register with the indentations in the end frame members. The

serrated surfaces of the end frame members 55 and the wedges are both tapered, so that, when the wedges are driven securely into position, there will be a satisfactory contact as between the wedges and the frame, that will insure a secure engagement without the 60 tendency to "rock".

It is evident, that the frame of the traveler will be adjustable to different widths of I-beam on which it is to travel, by merely removing the wedges, opening 65 the side frame members the desired distance, and then replacing the tapered and serrated wedges.

By this construction, a traveler will be 70 adaptable to many widths of I-beams.

There are no bolts or nuts to secure, and the ease and speed with which an adjustment can be made are desirable points in the construction.

Having thus described my invention, I 75 claim:—

1. In a device of the character described, a pair of side frame members carrying trolley wheels, and formed with perforations in their ends, a pair of end frame members 80 on which the side frame members are slidably mounted, said end frame members having elongated slots provided with serrations, and a series of wedge members having serrated surfaces and adapted to pass through 85 the perforations in the side frame members and to hold the side and end frame members in adjusted positions.

2. In a device of the character described, a frame made up of two perforated side 90 members and two end members, a set of trolley wheels carried by the side members, elongated, serrated slots in the end members, and serrated tapered wedges adapted to enter said perforations and hold the side 95 and end frame members in position.

3. In a device of the character described, a pair of end frame members having elongated slots provided with serrations and a pair of side frame members having wedge 100 receiving perforations and being adjustable on the end frame members, and a set of tapered and serrated wedges adapted to secure the end and side frame members in adjusted position.

In testimony whereof I affix my signature.

FRANK H. HOWARD.
